Primary Examiner — Steven J Czyz(74) Attorney, Agent, or Firm — Dunlap Bennett & Ludwig, PLLC(57) CLAIM

The ornamental design for a watercraft stand, as shown and described.

DESCRIPTION

FIG. 1 is a perspective view of a watercraft stand, showing my new design;

FIG. 2 is a right-side elevation view thereof;

FIG. 3 is a left-side elevation view thereof;

FIG. 4 is a front elevation view thereof;

FIG. 5 is a rear elevation view thereof;

FIG. 6 is a top plan view thereof; and,

FIG. 7 is a bottom plan view thereof.

In the drawings, the evenly-spaced broken lines depict portions of the article that form no part of the claimed design; the dash-dot-dash lines represent the boundary of the claimed design and forms no part thereof.
